E. C. WILLS

AUTOMATIC AND MANUALLY CONTROLLED CUT-OFF VALVE

Filed May 14, 1925

UNITED STATES PATENT OFFICE.

EDWIN COOPER WILLS, OF NEWARK, NEW JERSEY.

AUTOMATIC AND MANUALLY-CONTROLLED CUT-OFF VALVE.

Application filed May 14, 1925. Serial No. 30,347.

My present invention relates generally to the cut-off valves and more particularly to valves of the general type as described and claimed in my Patent No. 1,532,615, granted April 7th, 1925, my present invention dealing more especially with such a valve as used as a cut-off in gas feed lines and the like where as in the case of fire, it is essential to eliminate further supply of 10 gas.

My patent before referred to deals with the automatic closing of a valve in the presence of excessive heat and it has been found that in the installation of such valves it is 15 important in the first instance that the apparatus extend as little as possible above the valve casing in order to permit of its use in the gas lines of old buildings where the space is limited. It has also been found 20 expedient to provide manual means whereby the valve may be easily cut off from a distant point in case the fire within the building has not reached that particular point at which the valve is installed.

It therefore, becomes the primary object 25 of the present invention to provide both an automatic and manual control cut-off valve, the automatic controlling element being not only collapsible under excessive heat to permit closing of the cut-off valve but also being of such a nature and in connection with means permitting of its displacement from effective position so that the valve may be 30 manually released for closing from a distant point where it has not already closed under automatic control out of the excessive heat.

My invention as thus generally outlined 35 is shown in the accompanying drawing, which forms a part of this specification, and in which:

Figure 1 is a perspective view illustrating 40 the use of a manual and automatic control member;

Figure 2 is a side view partly in elevation 45 and partly in section of the form of the invention shown in Figure 1,

Figure 3 is a side view partly in elevation 50 and partly in section, illustrating a slight modification as regards the mounting of the controlling element of Figures 1 and 2, and,

Figure 4 is a detail perspective view illustrating 55 still another modified form of controlling member.

As shown in these figures and particularly 60 in Figures 1 and 2, the valve member 38 shifts vertically between valve seats 39

against the latter of which it seats in its lower effective position, as will be plain from the showing in Fig. 2. The upstanding stem 40 of the valve member projecting 60 above the cap 41 of the valve casing 42 has secured to its upper end a cross head 43 and to the outer ends of this cross-head 43, the upper ends of the valve actuating springs 44 are connected. The lower ends of these 65 springs are connected to lateral outstanding lugs 45 of the valve casing 42. The upper surface of the cap 41 forms a bearing point opposed to a nut 46 secured to the stem 40 with the cross-head 43, these two 70 bearing points being engaged when the valve and its stem are raised with the cross-head 43, by the bifurcated ends 47 and 48 of a pair of arms 49 and 50 constituting a controlling member. These arms are pivotally 75 connected to one another and also to the upper end of a supporting link 51, as indicated at 52, the supporting link 51 being connected at its lower end 53 to a lug 54 of the valve casing 42. The bifurcated ends 80 47 and 48 of the controlling arms are thus adapted to straddle the valve stem 40 and these portions of the arms are normally held in spaced relation by means of a controlling element consisting of a pair of straps 85 55 whose inner ends are secured in overlapping relation by a fusible solder as at 56. The outer ends of these straps have key-hole 90 slots adapted to engage laterally projecting studs 57 on the extensions 58 of the two arms 95 as in Figures 1 and 2, or the lateral projecting studs 59 in the arms 49^a and 50^a as indicated in Figure 3.

One of the extensions 58 of the arms serves 100 in the construction shown in Figures 1 and 2 to receive the adjacent end of the flexible control connection 60, while in Figure 3 it is of course obvious that one of the arms must have an extension 58^a for a similar purpose. In either case the soldered straps 55 hold the bifurcated ends of the controlling 105 arms in spaced relation so that they support the cross-head 43 spaced above the valve casing and hold the valve member open, until under excessive heat the solder is melted 110 when the controlling member as a whole collapses, and the cross-head descends under tension of the springs 44. Here too, the controlling element is so formed as to need only a fusible solder in order to permit of its reuse after each action. As indicated in Figure 4, the controlling member may consist

of two arms 60 and 61 having bifurcated ends 62 for use as in Figures 1 and 2 and having their opposite ends joined by means of fusible solder as at 63, one of the arms 5 being extended as at 64 to provide for pivotal connection with the supporting link as well as for connection with the manual controlling cord or wire 60.

As further shown in Figures 1 and 2, the 10 springs 44 may be accompanied by one or more weights 65 having apertures 66 to receive supporting pins upstanding from the cross-head 43 on which the weights are seated and to avoid relative displacement where 15 more than one weight is used by virtue of complementary openings and pins 67 connecting in the manner shown in Figure 2.

It is obvious that in either form of the invention the flexible cord or wire may be 20 extended in the front of the building and that pull upon this cord or wire results in lateral displacement of the automatic controlling element from its effective position so as to permit the valve to close. As before stated, this is especially desirable where 25 fire is present in the building but has not approached the location of the valve to the extent necessary to melt the soldered joint and bring about automatic closure of the 30 valve through the collapse of the automatic controlling element.

I claim:

1. A cut-off valve having a seat, means for 35 forcing the valve to its seat, means normally holding the valve off of its seat against the pressure of said first named means including a pair of arms having bifurcated ends, and a fusible connection normally holding the said bifurcated ends in spaced relation, and manual controlling means connected to one of 40 said arms for laterally displacing both of the arms from effective position.

2. A cut-off valve having a seat, means for 45 forcing the valve to its seat, means normally holding the valve off of its seat against

the pressure of said first named means and including a pair of valve controlling arms in pivotal connection with one another, fusibly connected straps in engagement with and normally spacing said arms in the effective 60 position, and manual controlling means in connection with said arms for laterally displacing the same bodily from the effective position.

3. A cut-off valve having a stem, a casing 55 having a seat for the valve, means engaging the stem of the valve for forcing the valve on to said seat, and means normally holding the valve off of its seat against the pressure of said first-named means, including a pair 60 of arms pivotally connected to one another and respectively engaging at one end the said casing and a portion of the valve stem, and a fusible connection normally holding said engaging ends of the arms in their spaced 65 apart effective position.

4. A cut-off including a valve having a stem, a casing having a seat therein, means engaging the said stem for forcing the valve on to said seat, and means normally holding 70 the valve off of its seat including a pair of arms pivotally connected to one another and respectively engaging the casing and a portion of said valve stem, and a pair of soldered straps in connection with said arms 75 and normally spacing the arms apart.

5. A cut-off including a valve having a stem, a casing having a seat therein, means engaging the stem for forcing the valve on to 80 said seat, means normally holding the valve off of its seat including a support pivotally connected at one end to said casing, a pair of arms pivotally connected to one another and to the other end of said support and respectively engaging at their free ends the 85 casing and a portion of the said valve stem, and a pair of soldered straps in connection with said arms and normally spacing the same apart.

EDWIN COOPER WILLS.
